UNITED STATES PATENT OFFICE.

DANIEL DAVIS, OF PORTLAND, MAINE.

TOE-PIECE FOR EDGE-TRIMMING MACHINES.

SPECIFICATION forming part of Letters Patent No. 316,750, dated April 28, 1885.

Application filed January 22, 1885. (No model.)

To all whom it may concern:

Be it known that I, DANIEL DAVIS, residing in Portland, in the county of Cumberland and State of Maine, have invented certain

5 new and useful Improvements in Toe-Pieces for Edge-Trimming; and I do hereby declare that the following is a full, clear, and exact description of the invention, which will enable others skilled in the art to which it appertains to make and use the same.

My said improvement relates to a new and useful toe-piece for use on that particular class of machines known in the boot and shoe factories as "edge-trimming machines."

15 I am aware that prior to my invention edge-trimming-machine toe-pieces have been made in a number of ways, but so far as I have been able to ascertain have always been objectionable for a variety of reasons. For example, when the shoes were set for edge-trimming, no support was provided for the shanks of the shoes on the inside while the outside edges of the soles were being trimmed. As a result the shanks of the soles would be pressed 20 inward, sometimes so far as to break the shanks and very materially impair the durability and value of the soles. Again, pressing the shanks inward would wrinkle or crease up the uppers to so great a degree that no subsequent stretching of the shoes could remove 25 the wrinkles, thus injuring the shape and fit of the shoes.

The object of my present invention is to furnish to the boot and shoe industry a toe-piece which shall be simple in construction, 35 inexpensive in cost, efficient in operation, and in every way well calculated to improve the character of the work done by edge-trimming machines.

40 To this end my improvement consists of a toe-piece provided at its rear part with a shank-supporting tongue, and having proper means for securely attaching the device to the instep-block or any other proper part of an edge-trimming machine.

45 That my improvement may be more particularly understood, reference should be made to the accompanying drawings, in which—

Figure 1 shows the toe-piece in position in 50 a shoe. Fig. 2 shows a sectional view of the toe-piece.

The same letters of reference indicate corresponding parts.

a shows the toe-piece proper. Extending from the back part of it, and passing over the 55 shank *b*, is a supporting-tongue, *c*. The parts *a* and *c* are integral.

The device may be made either of wood or metal, at the option of the user.

d shows a chamber cut out of the main 60 part *a*.

e designates a proper orifice to receive a screw-bolt, *f*, by means of which the device can be rigidly attached to any object.

This improvement was devised more especially for use on what is known as the "Dodge Trimming-Machine." On that machine is used an instep-block like *g*.

In attaching the toe-piece to the above-mentioned machine the chamber *d* is made to fit 70 over the tip of the instep-block *g*, after which the screw-bolt *f* is turned into place. Thus great rigidity of the parts is brought about.

In operating with my improvement the projecting tongue *c* fits closely over the shoe-shank and keeps it in its true position, so that all danger of the shank being strained and broken by inward pressure is obviated. Further, there is no danger that the shape of the upper of the shoe will be injured by reason of 80 wrinkles and creases.

I am aware that pegging-jacks have been provided with a toe-section of a last and an extensible heel portion, whereby the said toe portion can be forcibly pressed into a boot or 85 shoe previous to pegging the same. Such a device I hereby disclaim.

What I claim as new, and desire to secure by Letters Patent, is—

1. The toe-piece last-section connected with 90 a shank-tongue and a recess, in combination with an instep-block and a screw-fastening, substantially as and for the purposes described.

2. The new article of manufacture, consisting of a recessed toe-piece having a shank-supporting-tongue formed on it and adapted to be rigidly secured to the instep-block of a boot and shoe trimming-machine, substantially as 95 described.

In testimony that I claim the foregoing as my 100 own I have affixed my signature in the presence of two witnesses.

DANIEL DAVIS.
